US0D1070257S

(12) United States Design Patent (10) Patent No.: US D1,070,257 S
(45) Date of Patent: * Apr. 15, 2025

(54) PANTS

(71) Applicant: NIKE, Inc., Beaverton, OR (US)

(72) Inventor: Hee Ji, Portland, OR (US)

(73) Assignee: NIKE, Inc., Beaverton, OR (US)

() Term: 15 Years

(21) Appl. No.: 29/905,447

(22) Filed: Oct. 20, 2023

(51) LOC (15) Cl. 02-02

(52) U.S. Cl.

USPC D2/731; D2/742

(58) Field of Classification Search

USPC D2/742, 728, 731

CPC A41D 1/06; A41D 1/08

See application file for complete search history.

(74) Attorney, Agent, or Firm — Banner & Witcoff, Ltd.

(57) CLAIM

The ornamental design for pants as shown and described.

DESCRIPTION

FIG. 1 is a front, left side perspective view of pants showing my new design;

FIG. 2 is a left side view thereof;

FIG. 3 is a front, right side perspective view thereof; and,

FIG. 4 is a right side view thereof.

The area of the pants immediately adjacent to the solid lines depict portions of the pants that form no part of the claimed design. The broken lines depicting the remainder of the pants form no part of the claimed design.

1 Claim, 4 Drawing Sheets
